UNITED STATES PATENT OFFICE.

JAMES DUNNE, OF LONDON, ENGLAND.

OFFICE-DESK AND THE LIKE.

1,143,259.

Specification of Letters Patent. Patented June 15, 1915.

Application filed January 19, 1912. Serial No. 672,080.

To all whom it may concern:

Be it known that I, JAMES DUNNE, a subject of the King of England, residing at London, in England, have invented certain new and useful Improvements in Office-Desks and the like, of which the following is a specification.

This invention relates to office desks and is particularly designed for the use of registrars who have to deal with registers of births, marriages, deaths and so forth where books have to be constantly moved from place to place, as for example to be written in by the registrar and then turned to the informant for signature etc. Hitherto this has been a troublesome business and the books have suffered by being so constantly moved about, a difficulty which is overcome by the present invention.

According to this invention a registrar's desk comprises the combination of a nest of drawers, a top surmounting the drawers and providing a knee-hole for the user and a rotatable book-rest or carrier capable of rotary motion on the desk or table and preferably having also sliding motion thereon.

A portable book-rest is not claimed *per se* as it has previously been proposed to use a portable and rotatable book-carrier for supporting hotel registers so that it may be placed in any convenient position on the counter in the hotel to afford access to the register from both sides of the counter.

Other features of the invention will be more clearly understood with reference to the accompanying drawings in which:

Figure 1 is a perspective view of a desk embodying the present invention; Fig. 2 is a plan view of a portion of the desk; Fig. 3 is an end view partly in section of a modification of the present invention, and Figs. 4 and 5 show further modifications of details of the invention.

In the specific instance of a registrar's desk there is provided a desk A with a space A¹ at or near one end to accommodate the person who sits at the desk, and the other parts occupied by various drawers such as A², safe A³ and so forth arranged preferably with one key for the safe and another

key for all the drawers, the top of the desk being so far clear.

Conveniently placed for use of the sitter according to the modification shown in Fig. 1, is a turn-table book-carrying rest or desk B which consists of a central spindle C or equivalent about which the desk B turns, the latter being preferably arranged to accommodate two registers, although it may be arranged to accommodate more than two. Where only two books have to be accommodated, the desk would preferably consist of two sloping shelves or faces B¹, as illustrated, on which the books would lie open back to back or edge to edge so that when one book faces the sitter, the other will be turned away from him. These shelves are preferably provided with ledges B² and devices such as springs B³ for securing the leaves of the book in the open position if desired, and the turn-table device may be fitted with an appropriate means to secure it in any of its positions of rest. These means may in one construction take the form of a metallic ring sunk into or otherwise secured to the other side of the desk as shown in dotted lines in Fig. 2 at B⁴ and having holes formed therein at specified points for the reception of a spring-controlled detent such as a ball B⁵, shown in the construction illustrated in Fig. 3. By these means the desk may be held stationary in any position corresponding to the point in the metallic ring in which the holes are made but a slight force exerted in a direction tending to rotate the desk will, owing to the curvature of the ball, cause the latter to be depressed against the action of the spring and allow the desk to be rotated. Where the rotating desk is not arranged to slide the stop can be applied wherever found most convenient. A cover such as shown in dotted lines in Fig. 3 at B⁶ is preferably also provided and adapted to be locked, so that the books can be left open when not in use and yet be protected both from dust and illicit access. At night the books can be placed in the safe in the other portion of the desk.

In use, the registrar in writing his entries, 100

will have the book turned with the page facing him and in a convenient position for him to write at. When he has made the entry and it has to be signed by the informant, he turns the desk around so that the book in which he has made the entry now lies in front of the informant who can sign his name, and the desk can then be turned back again to face the registrar, or he can 10 turn the second register to him.

In a modified construction shown in Fig. 4, the central pillar or support upon which the desk rotates may be carried upon a slide D adapted to be moved backward or forward in a recess such as that formed in the member D¹. Preferably the slide and recess are of the dovetail type as shown in Fig. 5 or as a further modification the slide may form a portion of the pillar about which the 20 desk rotates as shown in Fig. 3. In all these constructions the recess may be formed in the top of the desk itself or a member having a recess formed in it may be secured to the desk to cover either the whole or only a portion of it. The slide recess will be 25 preferably formed in a part fixed to the main desk or in the main desk itself sufficiently far back to be out of the way of the registrar but capable of allowing 30 the central pivot or support to be drawn forward to the center of the desk so that the book-supporting rotatable member will lie above and centrally upon the main desk. Instead of sinking the pivot support in the recess, the recess may be formed in the bottom 35 of the pivot support, preferably with dovetailed edges so as to fit over a corresponding raised slide upon the fixed member.

After an entry has been made by the registrar he is not permitted to dry the ink, with which the entry has been made, by the aid of blotting paper but must allow the ink to dry naturally. Consequently there is provided a shield H which may be conveniently carried 45 upon an arm H¹ secured to the pillar C and jointed as at H² H³ to permit of its adjustment relatively to the desk B¹. The shield H after adjustment is adapted to be clamped in its position and after an entry has been 50 made in the register the desk is revolved until the book is under the shield by which it will be protected from damage and the ink will be protected from smearing. It is not, however, essential that the shield should be 55 supported from the central pivot or that it should be adjustable as it may be a fixture supported from the desk. The shield further prevents any person from surreptitiously reading an entry in the book covered 60 thereby.

It is often found that owing to various entries on the same page being quite similar to

look at when a copy is being made, the copyist is very apt to drop from one line or entry to another line or entry and to prevent it there is provided an attachment preferably secured to the revolving desk as follows:—The attachment consists of a shield E with an opening E¹ in it corresponding to the size of the space for a single entry so that the shield is placed upon the book and the only entry to be copied is visible through the shield which renders it impossible for the copyist to jump by mistake from one entry to another. This shield may be carried in various ways or 65 even made to be clamped to the book itself, but it is preferable to carry it on an arm F secured to the desk or to the central pillar C as shown in the illustrations, so that by moving the shield and arm the shield may be 70 placed in position upon the page and pressed there by a spring or other pressure as desired. In the drawings, a pivoted arm G and a clamping member G¹ at the end thereof take the place of the spring so that after the 75 shield has been moved into the desired position the arm supporting it may be clamped and held definitely in place. Conveniently the arm may be made with one or more universal joints such as G² G³ so that the shield can be turned in any direction and these joints or the shield or the arm generally may be spring-controlled so as to press the shield 80 upon the book.

It is sometimes difficult to read the entry 95 in a register, particularly signatures, and it is therefore often desirable to have some means of magnifying the writing; this may be provided either in connection with the shield or the opening in the shield may be 100 provided with a magnifying glass either made to slide along the opening or the opening may be filled with a fixed magnifying glass.

Although a particular construction and 105 modifications of the present invention have been described with reference to the accompanying drawings, it is obvious that many other modifications may be made in details in carrying the invention into effect provided always that the spirit of the invention 110 is not departed from.

What I claim as my invention and desire to secure by Letters Patent is:—

1. A rotatable book rest having a plurality 115 of inclined surfaces, each of said surfaces being arranged to support a book, a shield adjustable relative to said books, said shield being arranged to cover either of said books, and a spindle on which said book rest is rotatably mounted, the book rest being adapted 120 to be rotated with relation to the shield; substantially as described.

2. A book rest having a plurality of slop-

ing surfaces, each of which is arranged to receive a book, a spindle on which the book rest is rotatably mounted, a shield adjustably connected to said spindle and arranged 5 to cover one of said books, and a second shield adjustably connected to said spindle and arranged to cover a portion of one of said books, the second shield having a slot therethrough, said book rest being arranged

to be rotated relative to both of said shields; 10 substantially as described.

In testimony whereof I have signed my name to this specification in the presence of two subscribing witnesses.

JAMES DUNNE.
